William C. Baxter

UNITED STATES PATENT OFFICE.

WILLIAM C. BAXTER, OF BEVERLY, MASSACHUSETTS, ASSIGNOR TO UNITED SHOE MACHINERY CORPORATION, OF PATERSON, NEW JERSEY, A CORPORATION OF NEW JERSEY.

DELIVERY MECHANISM.

1,405,389.

Specification of Letters Patent. Patented Feb. 7, 1922.

Application filed July 23, 1919. Serial No. 312,814.

To all whom it may concern:

Be it known that I, WILLIAM C. BAXTER, a citizen of the United States, residing at Beverly, in the county of Essex and State 5 of Massachusetts, have invented certain Improvements in Delivery Mechanisms, of which the following description, in connection with the accompanying drawings, is a specification, like reference characters on the 10 drawings indicating like parts in the several figures.

This invention relates to machines for operating upon blanks. The invention is herein set forth by way of illustration with particular reference to its applicability to mechanisms designed to die out or otherwise form or operate upon blanks and to deliver the blanks after they are formed or operated upon. The illustrated machine is especially 20 designed to die out heel lifts for boots and shoes and to deliver the blanks in stacked relation. The invention, however, is not limited to application to this type of machine or to use for this purpose.

25 Machines for forming blanks as by dieing out heel lift blanks from sheet material commonly are constructed to discharge the blanks in a promiscuous heap. It is then necessary to sort the blanks, either arranging the blanks in stacks or placing them in proper relative positions in magazines, at the same time rejecting unusable and imperfect blanks and pieces of scrap. The sorting and stacking or magazining of blanks is 30 thus rendered excessively expensive. It has been proposed to provide a discharge or delivery mechanism extending out in front of such a machine substantially in line with the work supporting and blank feeding mechanism of the machine. Such a construction is 40 open to several objections, one of the most important being that it requires a disadvantageous or prohibitive amount of factory floor space.

45 It is an object of the present invention to provide a compact machine organization adapted for dieing out or otherwise forming or operating upon blanks which will be so constructed and arranged as to deliver the 50 blanks in position for ready removal in stacks and which, at the same time, will be comparatively simple and constructed so to deliver the blanks that they may be readily inspected before they are removed from the 55 machine.

It is frequently desired for the purpose of increasing the capacity of the machine to die out or otherwise operate upon a plurality of blanks simultaneously as by a double or multiple die. It is a further object of the invention to provide delivery mechanism adapted to be employed in connection with mechanism for dieing out or forming a plurality of blanks simultaneously which will be constructed to take the blanks from the dieing 60 out or forming mechanism and deliver them at a station convenient for removal in stacks as by delivery to a horizontal table in parallel stacks.

With these objects in view, the invention 70 provides a plurality of chutes leading from the dieing out or blank forming mechanism to a discharging station at one side of the blank forming mechanism. As herein shown and described and in accordance with 75 features of the invention, the delivery mechanism comprises a plurality of chutes or passageways for blanks arranged in parallelism and overlying at their receiving ends to adapt them to receive blanks from a 80 plurality of sources such as the discharge openings of a double or multiple die, the chutes being laterally offset between their receiving and delivery ends and terminating at their delivery ends in portions parallel 85 to each other and, as shown, in a horizontal plane to provide for conducting the blanks from the blank forming mechanism to a discharge station such as a table at one side of the blank forming mechanism and delivering the blanks to such table in a substantially horizontal plane in such manner as to expose the blanks for convenient inspection 90 and removal in stacks.

The above-mentioned and other features 95 and advantages of the invention will be apparent from the following detailed description and will be defined in the appended claims.

In the drawings, 100
Fig. 1 is a perspective view, partly in section, of a blank delivering mechanism, and
Fig. 2 is a plan view of the delivery end of the mechanism showing blanks in stacked relation as delivered by the chutes.

105 In the illustrative embodiment of the invention, the delivering mechanism comprises side plates 4, each having inturned flanges 6 provided with perforated projections 8 transversely aligned and through 110

which bolts may be passed to secure the side plates together. The upper ends of the side plates are secured to the under surface of a block 10 which supports, in the illustrative 5 construction, a double die 12, which is the cutting member of a heel lift cutting machine of well-known construction. Spacing the side plates 4 and serving as a partition to divide the delivery chute into two pas- 10 sageways is a member 14 the upper end of which is in alinement with and closely adjacent to the cross cutting bar 16 of the die 12. The other end of the member 14 ex- 15 tends to the point 18 where it is secured, said member thus forming the floor of one 20 passageway and the upper side of the other passageway. The fourth wall of each pas- 25 sageway in the chute is made movable and is shown to consist of a strip 20 or a strip 20 30 of sheet metal or other suitable material to which is secured pins or bolts extending through slots 24 in the plates 4 and carrying wing nuts 26 by which the pins or bolts may be secured in adjusted position in the 35 slots 24. By the means described, the strips 20, 22 may be accurately alined with the end portions of the cutter member or die 12 and hence as the blanks pass from the die they 40 will be received into the passageways on each side of the partition 14 and conducted to and along the independent chutes 28, 30 which are laterally offset from each other in order that the blanks may eventually be 45 delivered in rows in side-by-side relation- ship on a table or other support. While the chutes are shown combined in one structure adjacent the plate 10, it is clear that they may be constructed practically independent throughout. In addition to the supports al- 50 ready described for the wall 20, there is provided a bolt 32 passing through a slot 33 in the flange in one of the side members 4 and attached at its lower end to the strip 20 and to a continuation of said strip in the 55 form of a strip 34 (Fig. 2) which is also supported by wing projections 36 slotted to receive bolts which secure them to angle irons 38 on the inturned flange of the chute. Since the wing projections 36 and the angle 60 irons 38 have slots extending substantially at right angles to each other, the strips 34 may be readily adjusted to the size of the blanks passing through the chute, adjustment of the strip in the manner described 65 requiring movement of the strip longitudinally of the chute as well as toward and away from the upper flanges 40 of the chute. As may be inferred, the chute 30 is pro- 70 vided with a similar strip 34 or upper wall 60 for the passageway adjustably secured in place by means identical with that described in connection with chute 28.

In the construction shown, the side plates 4 of the first portion of the delivering mech- 75 anism are split at the point 18 to form the

side walls of the independent chutes 28 and 30, the side walls having inturned flanges similar to the flanges 6, above described, the partition 14 being continued from the point 18 as the floor of the chute 28, while the 70 plate or strip 22, which forms one wall of the passageway of the first portion of the delivering mechanism, is continued as the floor of the chute 30 resting upon inturned flanges similar to those shown at 6. As will 75 be observed, the free ends of the chutes 28, 30 rest upon and are secured to a table 42, while at intermediate points the chutes are secured by braces 44 to a member 46 which constitutes part of the supporting structure 80 for the delivering mechanism. Since the sides of the delivery chutes are secured to the plate 10 and to the supporting member 46 and to the table 42 by means which hold them firmly in position, the bolts, which may be arranged to pass through the flanges 8, may be supplied at only necessary points. As a means of strengthening the chutes 85 and 30 and holding them in the desired relative position, they are interconnected by 90 means of a curved plate 48 secured to brackets 50 attached to the sides of the chutes. 95

As will be seen from an inspection of Fig. 2, of the drawings, the chutes 28 and 30 end in portions which are arranged in 100 parallelism and practically in the same horizontal plane in order that the streams of blanks coming from the chutes may be located in a position readily accessible to the attendant who is to remove the blanks for 105 the purpose of stacking them for packing, or for other purposes, as, for instance, in magazines for use in other machines. In the construction shown, the chutes end at the edge of the table 42, though obviously 110 the sides of the chutes may be extended across the table in the form of open trough-shaped members 52 which receive the blanks as they issue from the chutes. Preferably these trough-shaped members 52 are made 115 of pieces of wood of considerable thickness so as not to present any sharp edges to the hands of the attendant. It will be evident that the stream of blanks when thus exposed may be readily inspected by the attendant to the end that imperfect blanks or 120 scraps of material may be rejected and perfect blanks be readily removed in the stacked relation in which they appear wherein all of the blanks are positioned with 125 their analogous edges facing all in the same direction, thus making it unnecessary to perform any assorting operation. As will be observed from an inspection of Fig. 2, the blanks in the chute 28 have their con- 130 vexly curved edges all facing upwardly, while in the chute 30 the straight edges of the blanks face upwardly.

In the blank forming machine of which the double die 12 is an essential element, 130

the strips of material from which the blanks are formed are fed across the face of the die in either direction at right angles to the long axis of the die. Inasmuch as the feeding mechanism which is ordinarily provided to carry out this operation of feeding the material to the die takes considerable space, it was found advisable to have the delivering mechanism extend in another direction from the cutting machine and not in alinement with the feeding mechanism in order that the machine might occupy less floor space in one direction and still present the delivery table in the best light at the window. Hence the delivering mechanism is so constructed that at its blank receiving end one chute or blank carrying passageway lies above another chute or passageway and if this relative position of the chutes continued throughout the blanks would normally be delivered in streams one above another in a manner which would make it difficult or impracticable to handle the blanks properly. In order to deliver the streams of blanks in side-by side relationship, the chutes are laterally offset at an angle to each other throughout a portion of their lengths and finally are brought into practically parallel relationship with the delivery ends in substantially the same horizontal plane, thus adding greatly to the ease with which the attendant may inspect the blanks and remove the same, as described. In the illustrative construction, the parallel portions of the chutes are in vertical planes which are parallel to the vertical plane of the combined chutes at their blank receiving ends.

In the operation of cutting machines of the kind in which a die is the cutting element, the blanks are formed intermittently and forced step-by-step along the chute, the freshly cut blanks forcing those which preceded them along the chutes until they appear at the delivery end of the mechanism. Because of the efficient arrangement disclosed, it has been found that the attendant may readily take care of the product of the commercial heel lift cutting machine, for instance, which has a capacity in the neighborhood of 500 lifts per minute. Previously it required constant work on the part of several individuals to sort the perfect lifts from an occasional imperfect lift or piece of scrap and position the lifts with their analogous edges pointing all in the same direction for stacking, for packing purposes, and for introduction into magazines.

Having thus described my invention, what I claim as new and desire to secure by Letters Patent of the United States is:—

1. In a device of the class described, delivery chutes having blank receiving portions arranged side by side in one plane for

receiving blanks from a plurality of sources of supply and having relatively offset portions ending in portions parallel to each other and with said plane and so arranged that the space above each end portion is unobstructed, for delivering the blanks to a table or other support in positions readily accessible to the workman. 70

2. In a device of the class described, a delivery chute having a portion divided into a plurality of passages for receiving blanks from a plurality of sources and having laterally offset portions each forming an independent chute for delivering the blanks to a table or support in a position readily accessible to the workman. 75

3. In a device of the class described, a delivery chute having a portion divided into a plurality of passages for receiving blanks from a plurality of sources, and having laterally offset portions each forming an independent chute, the chutes thus formed being arranged in parallelism for a part of their length and having open trough shaped portions in substantially the same horizontal plane so that the blanks are disclosed in the open troughs in stacked relation as they progress from the chutes. 85 90

4. In a device of the class described, a mechanism for making a plurality of blanks simultaneously, chutes for receiving the blanks from the mechanism and arranged to lead away therefrom in such manner that one chute overlies another, the chutes having portions which are offset laterally from each other, and other portions parallel to each other in a substantially horizontal plane, and a table or support having trough shaped members serving as extensions of the chutes to receive the blanks as they progress in stacked relation from the chutes. 95 100 105

5. In a machine of the class described, a die operative to cut a plurality of blanks from strip material fed to the die, and a plurality of chutes for carrying the blanks away from the die in a lateral direction at a substantial angle to the direction or path of the strips as they are fed to the die, said chutes having their delivery ends parallel to each other in substantially the same horizontal plane so that the blanks are delivered on a table or other support in parallel streams or rows. 110 115

6. In a machine of the class described, a die operative to cut a plurality of blanks from a strip of material fed to the die, and delivery chutes for receiving the blanks from the die and having delivery portions arranged laterally of each other to deliver the blanks in streams or rows in side-by-side relationship, the receiving ends of the chutes and the delivery ends being in planes which intersect at right angles the path of the strips as they are fed to the die. 120 125 130

7. In a machine of the class described, a die operative to cut a plurality of blanks from strip material fed to the die, and a plurality of chutes for carrying the blanks away from the die in a lateral direction at a substantial angle to the direction or path of the strips as they are fed to the die, said chutes having their delivery ends displaced laterally of each other and arranged to deliver the blanks on a table or other support in streams or rows with the space above each unobstructed whereby the blanks are open to inspection and free for removal in their stacked relation.
8. In a machine of the class described, a die operative to cut a plurality of blanks from a strip of material fed to the die, and delivery chutes for receiving the blanks from the die and having portions along which the blanks pass in streams or rows one above another and having delivery portions arranged laterally of each other to deliver the blanks in streams or rows in side-by-side relationship with the space above each stream or row unobstructed so that the blanks are open to inspection and free for removal in their stacked relation.
9. In a machine of the class described, a double die for cutting heel lifts from strips of material in such manner that the breast edges of the lifts cut at each operation are adjacent to each other, and delivery chutes for receiving the lifts from the die and arranged to deliver them in streams or rows in side-by-side relationship with the lifts in one row having their breast ends pointing upwardly and those of the other row with their convex edges pointing upwardly.
10. In a machine of the class described, a plurality of cutting means for forming blanks in sets from sheet material with the blanks in each set having certain of their analogous edges closely adjacent each other, and certain others of their analogous edges facing away from each other, and delivery chutes for receiving the blanks in the described relation and having portions for delivering the blanks in streams or rows in side-by-side relationship with the described analogous edges in both cases facing in directions away from each other.

In testimony whereof I have signed my name in this specification.

WILLIAM C. BAXTER.
